(57) **CLAIM**

The ornamental design for a semi-round floor drain, as shown and described.

DESCRIPTION

FIG. 1 is a perspective view of a semi-round floor drain in accordance with the present invention; FIG. 2 is a top plan view thereof; FIG. 3 is a left elevational view thereof; FIG. 4 is a bottom elevational view thereof; FIG. 5 is a right elevational view thereof; FIG. 6 is a front elevational view thereof; and, FIG. 7 is a rear elevational view thereof.

The broken lines shown in the drawings illustrate portions of the semi-round floor drain and screws used with the semi-round floor drain that form no part of the claimed design.

1 Claim, 4 Drawing Sheets

Matter enclosed in heavy brackets [ ] appears in the original patent but forms no part of this reissue; matter printed in italics indicates the additions made by reissue.
